Patented Feb. 24, 1959

184,501

COMBINED HELICOPTER AND AUTOMOBILE

Walter F. Wlaschin and Hilbert W. Nieman,
St. Paul, Minn.

Application November 7, 1957, Serial No. 48,366

Term of patent 14 years

(Cl. D71—1)

Fig. 1 is a view in top plan of a combined helicopter and automobile showing our new design;

Fig. 2 is a view in side elevation; and

Fig. 3 is a view in end elevation.

The opposite side and end are substantially identical with the side and end shown in Figs. 2 and 3.

We claim:

The ornamental design for a combined helicopter and automobile, as shown and described.
